VENDING VEHICLE FOR SOFT ICE CREAM

Thomas Carvel, Chauncey, N. Y.

Application March 20, 1958, Serial No. 50,113

Term of patent 14 years

(Cl. D14—3)

Fig. 2

Fig. 1 is a perspective view of a vending vehicle for soft ice cream, showing my new design; and

Fig. 2 is a front elevation thereof.

Both sides of the vehicle are substantially the same.

I claim:

The ornamental design for a vending vehicle for soft ice cream, substantially as shown and described.
